[57] CLAIM

[**] Term: 14 Years

The ornamental design for a motor home front panel
unit exterior surface, as shown and described.

DESCRIPTION

FIG. 1 is a front perspective view of the motor home
front panel unit exterior surface, illustrating my new
design;

FIG. 2 is a left side elevation view thereof, with the
right side being substantially a mirror image;

FIG. 3 is a top plan view thereof; and,

FIG. 4 is a front elevation view thereof.
